UNITED STATES PATENT OFFICE

1,952,734

ELECTRIC FUSE DEVICE

John A. Ten Brock, Mount Airy, Pa.

Application July 26, 1932, Serial No. 624,712

8 Claims. (Cl. 200--126)

The subject of my invention is an electric fuse device. One element of the device is the fuse proper or a member adapted to volatilize, explode or otherwise generate pressure upon the passage 5 of an excessive current therethrough.

Another element is a switch or pair of contacts adapted to be separated by the excess pressure generated.

A third element consists of a liquid, viscous, 10 resilient, flexible or solid dielectric material arranged to be interposed between the two contacts of the switch when the latter are separated to extinguish the arc or to prevent the reestablishment thereof.

15 For a further exposition of my invention reference may be had to the annexed drawing and specification at the end whereof my invention will be specifically pointed out and claimed.

In the drawing,

20 Figure 1 is a side elevation of my device with parts broken away in vertical cross section showing the switch in closed position.

Figure 2 is a side elevation of a modification 25 of my device with parts broken away in vertical cross section showing the switch in open position.

Figure 3 is a view similar to Figure 2 of another modification.

The embodiment of my device chosen for illustration in the drawing is a type of fuse device 30 for use to protect transformers of electric distributing systems. In this embodiment the device comprises a hollow terminal 1 having a cap or other closure 2 therefor. This cap or closure is adapted to receive the fuse proper which consists of two spaced electrical contacts 4 and 5, one of which is in contact with the cap 2 and the other of which is in contact with the terminal 6 of the switch hereinafter mentioned. Contacts 4 and 5 are separated by insulation 3 which in 40 the modification shown encloses two grains of gun powder (not shown). Contacts 4 and 5 are connected by a fusible strip 33.

Terminal 1 also surrounds an insulating bushing 7 which has a shoulder 8 at the lower end 45 thereof cooperating with the shoulder 9 on contact 6 to support the contact. Bushing 7 is supported by the screw threads 10 on the lower internal side of terminal 1 or by the tube 16 which is connected to the screw threads.

50 The switch consists of contact 6 which, as shown in Figure 1, has a hollow, tapered interior. Fitting into this tapered interior is a cooperating contact 11.

Within contact 6 is mounted a dielectric, generally indicated at 12, which may be either liquid,

viscous, flexible, resilient, or solid. As shown in this modification it consists of a glass tube 13 surrounding a body of non-conducting liquid 14, such as carbon tetrachloride. Dielectric 12 is supported on a washer 15 of insulating material. 60

The threads 10 on the lower end of terminal 1 cooperate with threads on the upper end of insulating tube 16 which serves to space terminal 1 from the lower terminal 17. Tube 16 may conveniently be made of a material which possesses 65 mechanical strength and high insulating qualities. Tube 16 is shown as being circular in cross section but it may be square, rectangular or of any other convenient shape. Contact 11 is electrically connected to terminal 17 by cable 18 70 which is firmly attached to terminal 17 as by screw 19. Terminal 17 carries at its lower end cap 20 having a perforation 21 therein through which cable 18 passes loosely.

The operation of my device is as follows:—In 75 normal operation the fuse is connected into the line by means of clips (not shown) which engage the outer surfaces of terminals 1 and 17 so as to hold the fuse device in the upright position shown in the drawing. Upon the passage of a current 80 of the magnitude against which the fuse device is designed to protect the circuit to which it is connected, the fuse (elements 3, 4 and 5) blows, volatilizes, explodes or otherwise generates pressure. This pressure is transmitted through the 85 interior of contact 6 to washer 15 and contact 11. Due to the tapered fit between contacts 6 and 11, the latter is expelled from contact 6. The force of the pressure generated breaks glass 13 and holds liquid 14 and washer 15 against the 90 end of contact 11. This causes the arc which is drawn between contacts 6 and 11 to be of a hollow tubular shape since the arc must jump around the edge of the dielectric washer 15 and the dielectric 14 in contact therewith. The force 95 of the explosion and the movement of contact 11 in tube 16 is slightly cushioned by the air in tube 16 and terminal 17, the air being slightly compressed due to the restricted area of hole 21 through which it must escape. Contact 11 is also 100 cushioned by the tendency of cable 18 to coil upon itself to form a resilient mass as is best seen in Figure 2. Contact 11, cable 18 and orifice 21 are so proportioned that contact 11 is brought to rest slightly below the end of tube 16 so that 105 dielectric washer 15 is still within the end of the tube 16, as is best seen in Figure 2. The dielectric 14 surrounds washer 15 and fills up any interstices between washer 15 and tube 16 so that the dielectric is interposed into the arc drawn 110

between the contacts 6 and 11 and completely smothers the arc and prevents its reestablishment. The fuse device may be restored to its original condition by dismantling the parts and inserting a new fuse and fresh dielectric and re-engaging contacts 6 and 11 in the position in which they are shown in Figure 1. Contacts 6 and 11 may conveniently be compressed together so that it requires a pressure of 300 lbs. to separate them.

The modification of my device shown in Figure 2 is the same as that shown in Figure 1 except that a viscous dielectric 114 is employed instead of the liquid dielectric 14 shown in Figure 1. The viscous dielectric 114 may conveniently be petroleum jelly or any other grease having a high dielectric or insulating property. The dielectric 14 may be simply packed within contact 6 and supported upon washer 15 or supported directly upon contact 11 with washer 15 omitted.

The modification shown in Figure 3 is similar to that shown in Figures 1 and 2 except that a solid dielectric 115 is employed. This dielectric consists in lengthening the washer 15 of Figure 1 to a considerable length so that when the fuse device has operated, the dielectric 115 extends to a considerable distance into tube 16 and thereby interposes, an almost solid dielectric barrier consisting of tube 16 and washer 115 between the contacts 6 and 11. When a dielectric of the type disclosed at 115 in Figure 3 is employed, the dielectric 115 may conveniently be made of a resilient or flexible insulating material so that the dielectric mushrooms or spreads over the end of tube 16 thereby forming a solid dielectric barrier between the contacts 6 and 11.

I do not intend to be limited in the practice of my invention save as the scope of the prior art and of the attached claims may require.

I claim:

1. An electric fuse device including in combination, a fuse adapted to generate pressure upon the passage of an excessive electric current therethrough, a pair of contacts arranged to separate under said pressure, a solid dielectric arranged adjacent said contacts, and a fluid dielectric other than said fuse arranged within one of said contacts, said solid dielectric and said fluid dielectric being arranged to move into position between said contacts when they are separated to extinguish the arc therebetween.

2. An electric fuse device including in combination, a casing, a fuse in said casing adapted to generate pressure upon the passage of an electric current therethrough, a pair of contacts in said casing arranged to be separated by said pressure, means for cushioning and stopping the movement of one of said contacts within said casing, and a dielectric arranged to be interposed between said contacts when they are separated.

3. An electric fuse device including in combination, a casing, a fuse in said casing adapted to generate pressure upon the passage of an excessive electric current therethrough, a pair of contacts arranged so as to be separated by said pressure, a cable connected to one of said contacts for conducting current thereto when said contacts are closed, means including said cable for cushioning said contact within said casing to stop it after movement, and a dielectric arranged to be interposed between said contacts when they are separated.

4. An electric fuse device including in combination, a fuse adapted to generate pressure upon the passage of an excessive electric current therethrough, a hollow contact arranged adjacent said fuse to receive said pressure, a movable contact having a tapering fit with said hollow contact and adapted to be separated therefrom by said pressure, and a dielectric in addition to said fuse arranged within said hollow contact when the contacts are closed and arranged to be interposed between said contacts when they are separated.

5. An electric fuse device including in combination, a fuse adapted to generate pressure upon the passage of an excessive electric current through it, a pair of contacts arranged so as to be separated by said pressure, a solid dielectric arranged adjacent said contacts, and a viscous dielectric in addition to said fuse arranged adjacent said contacts, said solid dielectric and said viscous dielectric being arranged so as to be interposed between said contacts when they are separated.

6. An electric fuse device including in combination, a fuse adapted to generate pressure upon the passage of an excessive electric current therethrough, a pair of contacts arranged to be separated by said pressure, a tube of insulating material within which one of said contacts is moved by said pressure, and a dielectric arranged so as to cooperate with said tube to form a complete dielectric barrier between said contacts when they have separated.

7. An electric fuse device including in combination, a pair of terminals, an insulating tube cooperating with said terminals to form a casing, a fuse in said casing, a means for said fuse adapted to melt upon the passage of an excessive electric current therethrough and to generate pressure, a pair of contacts mounted within said casing adjacent one end of said tube and adjacent said fuse, said contacts being adapted to separate under said pressure, means adjacent the opposite end of said tube for cushioning and stopping one of said contacts upon its movement, a solid dielectric mounted adjacent said contacts, a second dielectric mounted adjacent said contacts, said solid dielectric and said second dielectric being arranged to cooperate with said tube to form a complete dielectric barrier between said contacts when they have separated.

8. An electric fuse device including in combination, a fuse adapted to generate pressure upon the passage of an excessive current therethrough, a stationary contact adjacent said fuse, a movable contact adapted to be separated from said stationary contact by said pressure, and a dielectric other than said fuse interposed between said fuse and said movable contact.

JOHN A. TEN BROOK.
